UNITED STATES PATENT OFFICE.

JAMES DEARMANN, OF MILWAUKEE, WISCONSIN, ASSIGNEE TO MILWAUKEE IGNITION COMPANY, OF MILWAUKEE, WISCONSIN, A CORPORATION.

GASOLINE VAPORIZER.

Application filed December 10, 1926. Serial No. 153,827.

This invention relates to gasoline vaporizers.

Objects of this invention are to provide a device which may be attached between the carburetor and the intake manifold of a gasoline engine, and which is actuated by the suction of the engine in a manner to cause the thorough homogenizing of the mixture, and the thorough atomization and breaking up of all particles of the liquid, which may pass to this portion of the system.

Further objects are to provide a rotary device which is enclosed in a small casing easily attached between the carburetor and the intake manifold, and so constructed that it will insure a perfect mixing of the air and gas, and will also bring in and mix a small additional stream of air with the mixture so that a very perfect mixture results.

Further objects are to provide a device which is extremely simple and may be cheaply produced and readily applied, and which is so constructed that it is fool-proof and does not require any attention whatsoever on the part of the operator.

Further objects are to provide a device which will trap a small amount of fuel when the engine is stopped, and which will lift this fuel up and mix it with the flowing stream of air or mixture passing to the engine and thus aid in the easy starting of the engine.

An embodiment of the invention is shown in the accompanying drawings in which:

Figure 1 is a sectional view through the device showing a portion of the carburetor and intake manifold, such view corresponding to a section on the line 1—1 of Figure 2;

Figure 2 is a sectional view on the line 2—2 of Figure 1;

Figure 3 is a rear view of the apparatus showing it detached from the manifold and having a portion broken away for clearness of illustration.

Referring to the drawings, it will be seen that the outlet portion of the carburetor is indicated by the reference character 1, and that the intake manifold is indicated by the reference character 2. The carburetor and manifold are provided with attaching flanges 3 and 4 between which the device is placed.

The device comprises a front casing 5 and

a rear casing 6 which are provided with 55 cylindrical recesses which together form a main recess of cylindrical contour for the reception of the rotary member hereinafter described. These two sections of the casing are bolted together by means of the lower 60 bolt 7, and by means of the attaching bolts 8 which pass through the flanges 3 and 4. Further, it is to be noted that the casing 6 has a slightly larger internal aperture than the casing 5, and that the casing 5 is provided with a marginal flange 9 which fits within the aperture of the casing 6 and has a snug fit therewith to make an air-tight and fuel-tight joint. The casing 6 is provided with an elongated boss 10 on its rear 70 side provided with an aperture 11 through which air may be drawn, such air discharging into the casing by means of a right angle aperture 12, as shown most clearly in Figure 3.

It is to be noted from Figure 1 that the casing 6 is provided with an entrance aperture 13 adjacent the upper portion of the main aperture and preferably this entrance aperture tapers, as indicated. Further, the 80 casing 5 is provided with a short, projecting tubular portion 14 which fits within the intake manifold 2.

The rotary member comprises a hub portion 15 provided with a plurality of radially arranged slanting vanes 16. The outer ends of the vanes are joined by a peripheral band 17 to secure strength of construction.

The rotary member is carried by the enlarged central portion of a pin, as indicated at 18, such pin being provided with smaller terminal portions 19 which fit within corresponding apertures formed in the main casing.

The main casing can not become distorted or bowed inwardly to interfere with the action of the rotary member, as the parts are rigidly braced at their periphery, and are also braced at their central portions by means of the enlarged portion 18 of the 100 central pin.

The rotary member freely rotates upon the pin, a sufficient amount of lubricant being carried by the gasoline.

In the operation of the device, the mixture passes through the opening 13 and through the tubular portion 14 into the intake manifold. This causes a very rapid ro-

tation of the rotary member and the vanes thereof break up any solid particles of fuel, and cause a homogenizing of the mixture. Further than this, it has been found in actual tests conducted with this apparatus that the fuel is thoroughly and completely vaporized, and that a substantially perfect mixture results.

It is to be noted that the rotary member is extremely light and travels at an enormous rate of speed with consequent thorough mixing of the parts of the flowing stream. In addition to this, a small stream of fresh air is drawn through the openings 11 and 12 to an intermediate portion of the rotary member, and this air is thrown outwardly by the rotary member and thoroughly mixed with the flowing stream.

In actual tests conducted with this apparatus, it has been found that it may be interposed between the usual carburetor and the manifold, and that it will vastly increase the mileage per gallon of fuel.

Further, it is to be noted that the apparatus aids in the easy starting of the engine, as it will pocket any small amount of liquid fuel that may collect. Upon starting the engine the vanes churn up this fuel and mix it with the flowing stream of air or mixture, and thus insures a rich mixture passing to the engine.

It will be seen further that the device is very simple in construction and may be sold at a very small price. It is wholly fool-proof and requires no thought on the part of the operator.

Although the invention has been described in considerable detail, such description is intended as illustrative rather than limiting as the invention may be variously embodied and as the scope of such invention is to be determined as claimed.

I claim:

1. A gasoline vaporizer for use in connection with internal combustion engines, said vaporizer comprising a casing adapted for attachment between the carburetor and intake manifold of an engine and having a cylindrical internal cavity, a transverse pin carried by said casing centrally of the cavity, a rotor revolvably mounted upon said pin and having a plurality of radially slanting vanes, said casing having a passageway formed therethrough and constituting a continuation of the cavity through said carburetor and intake manifold, said passageway being eccentric with reference to said cylindrical cavity, said vanes projecting part way across such aperture.

2. A gasoline vaporizer for internal combustion engines comprising a casing having a vertical cylindrical cavity formed therein and adapted to be clamped between the intake manifold of an internal combustion engine and the carburetor, said casing having an opening passing therethrough and communicating with said cavity and connecting said intake manifold and said carburetor, a rotary member mounted within the vertical cavity of said casing and having a plurality of radial angularly set vanes, whereby the passage of the mixture through the aperture in the casing will rapidly rotate said rotary member and cause complete vaporization of the passing mixture, said cylindrical cavity being eccentric with reference to said opening and extending below said opening and stopping short of the top of said opening.

In testimony that I claim the foregoing I have hereunto set my hand at Milwaukee, in the county of Milwaukee and State of Wisconsin.

JAMES DEARMANN
